UNITED STATES PATENT OFFICE

137,710

DESIGN FOR A CASING FOR FOURDRINIER SHAKE

William M. Leeson, Glens Falls, N. Y.

Application December 2, 1943, Serial No. 111,876

Term of patent 14 years

(Cl. D59—9)

To all whom it may concern:

Be it known that I, William M. Leeson, a citizen of the United States, residing at Glens Falls, in the county of Warren and State of New York, have invented a new, original, and ornamental Design for a Casing for Fourdrinier Shake, of which the following is a specification, reference being had to the accompanying drawing, forming part thereof.

Fig. 1 is a plan view of the casing for a Fourdrinier shake showing my new design;

Fig. 2 is a side elevational view of the casing shown in Fig. 1; and

Figs. 3 and 4 are opposite end elevational views of the casing shown in Figs. 1 and 2.

I claim:

The ornamental design for a casing for Fourdrinier shake, as shown.

WILLIAM M. LEESON.
